UNITED STATES PATENT OFFICE.

WILHELM SCHUSTER, OF MEDFORD, WISCONSIN.

STUMP-PULLER.

SPECIFICATION forming part of Letters Patent No. 328,720, dated October 20, 1885.

Application filed August 29, 1885. Serial No. 175,623. (No model.)

To all whom it may concern:

Be it known that I, WILHELM SCHUSTER, of Medford, in the county of Taylor, and in the State of Wisconsin, have invented certain 5 new and useful Improvements in Stump-Pullers; and I do hereby declare that the following is a full, clear, and exact description thereof.

My invention relates to stump-extractors; 10 and it consists in the construction and arrangement of the several parts, as will be fully described with reference to the accompanying drawings, in which—

Figure 1 is a perspective view showing my 15 stump-extractor in operative position; Fig. 2, a sectional plan view through line *x x*, Fig. 3; Fig. 4, a front elevation, partly in section; Fig. 5, a detail view of connecting-rods and their coupling-shackle, and Fig. 6 a top plan 20 view of the shaft-head.

In the drawings is represented a supporting-frame having vertical standards *a a*, united by horizontal cross-pieces *b b'*, the lower one, *b'*, of these cross-pieces having a greater width than 25 the upper one, and formed with a central circular opening to receive the foot of and act as a bearing for a shaft or drum, *A*, the bearing for the upper portion of said drum or shaft being formed by half-circular openings 30 respectively cut in the upper cross-piece, *b*, and an auxiliary cross-piece, *c*, the latter being supported by brackets *c' c'*, bolted to the vertical standards *a a*, and coming flush against the former.

Secured by hooks *d* or other suitable means 35 to the forward portion of the supporting-frame is a guideway, *C*, in which travels a block, *D*, having therein grooved pulleys or sheaves *d' d''*, and provided at its front end with a tongue, *d''*, to receive the shackle *E* of a connecting- 40 rod, *F*, said shackle preferably consisting of a single piece of metal cast or swaged out so as 45 to have a central web and U-shaped ends, the latter provided with openings to receive a pin or bolt by which the coupling is completed.

Secured on the lower horizontal cross-piece, *b'*, and against the vertical standards *a a*, are blocks *e e*, to the upper faces of which blocks 50 are pivotally fastened spring-pawls *f f*, which engage notches *g g*, cut in the lower portion of the shaft or drum *A*, and a binding-ring, *G*,

which ring encircles said shaft or drum, and in connection with its cut-away portion or lower journal, *h*, of the latter forms a shoulder, against which rests the rear end of a lever, *H*, 55 fulcrumed at *h'* to the lower cross-piece, *b'*.

The upper portion of the shaft or drum *A* is cut away to form a journal, *h''*, and shoulder *h'''*, said journal bearing in the circular opening formed by the cut-out portions of the cross- 60 pieces *b c*.

Above the upper journal portion of the shaft *A*, and formed integral therewith, is a tenon, *I*, and short shaft *i*, as more clearly illustrated by Fig. 5, said short shaft having cut therein 65 a slot for the reception of a key, *i'*, the latter suspending the main shaft or drum in operative position. The tenon *I* is designed to fit a correspondingly-formed mortise in the block *K* upon the under side of a tongue, *L*, and interposed between the said block and the cross-pieces *b c* of the supporting-frame is a loose 70 collar, *k*. To the forward sides of the cross-pieces *b b'* are secured uprights *l l'*, the former being slotted near its lower end to receive a pulley, *m*, set in a stirrup, *m'*, said stirrup being fitted in the upright, so that the inner faces of its sides are flush with the inner faces of the slot in said upright, and act as a guide for the drawing-rope. 75

Secured to a hanger, *n*, upon the top of the upright *l* is a cord, which passes down under a pulley in the top of a traveler-frame, *M*, then up over and down from a pulley, *o*, set in a slot in the upper end of the upright *l'*, said 80 cord having secured to its free end a weight, *o'*, said traveler-frame operating in guides *l' l'*. The lower portion of the traveler-frame has journaled therein a pulley, *p*, over which travels the drawing-rope *N*, which is secured at 85 one end to the cross-piece *b'* by a socket, *r*, and eyebolt *r'*, the latter being driven in said cross-piece, as shown by dotted lines in Fig. 2. The free end of this rope *N* is passed under and over the pulley *d'* in the block *D*, thence 90 back over and under the pulley *m*, secured in the slotted upright *l*, then forward under and over the pulley *d''* in said block *D*, then back over the pulley *p* in the traveler-frame *M*, and made fast to the shaft or drum *A*. 95

The tongue *L* is braced at its rear end by longitudinal pieces *s s*, bolted thereto, and fur- 100

ther secured by means of a strap, *t*, and at the forward end of said tongue is bolted an equalizer consisting of a spring, *O*, and eye-rod *u*.

In the operation of my invention the supporting-frame is secured to any convenient object by means of a chain passed through eyes formed by the bends in stay-rods *R R*, which rods have their ends connected by links and eyebolts to the rear end of said supporting-frame. The pulley-block *D* being run out upon the guideway *C* and the rope *N* almost or entirely unwound from the shaft or drum, *A*, a coupling-rod, *F*, is then united by the shackle *E* to the tongue *d* of said pulley-block, and a chain, *S*, secured to an eye in the forward end of this coupling-rod is thrown around the stump to be extracted. Where the stump or stumps to be extracted are at a distance from the extractor, connection is made by splicing a sufficient number of the rods *F* by means of shackles *E*, as shown in Fig. 4. The tongue *L* being rotated, the shaft or drum *A*, keyed and suspended to said tongue, is revolved, and the rope *N* winds thereon, and the block *D*, made fast to the stump through the medium of its tongue *d* and the connecting rod or rods *F* and chain *S*, travels back on the guideway *C*. As this operation is continued great force is exerted against the stump to finally draw it up out of the ground. The weighted traveler *M* guides the rope *N* and causes it to wind in even coils upon the shaft or drum. Said rope being slightly heavier than the counter-weight *o*, the latter is gradually drawn up as the former comes in. As the shaft or drum is revolved in a direction to wind the rope the spring-pawls *f f*, which are rounded upon their outer forward ends, slip in and out of the notches *g g* in said shaft, these notches being also rounded upon one of their side faces to permit the play of the pawls. The inner faces of the pawls and their opposing faces in the notches are squared, so as to hold and prevent a reverse motion of the shaft or drum should a break occur or it be found desirable at any time to discontinue the operation of the extractor.

After the stump has been extracted, and it is desired to repeat the operation above described, the key *i'*, which suspends the main shaft or drum in operative position, is withdrawn and the latter revolved enough to disengage the spring-pawls. This operation being accomplished, the main shaft or drum will of its own gravity drop down until the shoulder formed by its lower cut-away portion, *h*, and the binding-ring *G* rests against the rear end of the lever *H*, interposed between the binding-ring *G* and the lower cross-piece, *b'*. By this operation the tenon *I* is disengaged from its mortise in the rear portion of the tongue *L*, said tongue then resting upon the loose ring *k*, which ring is now occupied by the tenon, and the mortise by the short shaft *i*, which shaft revolves freely therein. The tongue and shaft being now disengaged, the block *D* can be drawn out upon its guideway

C and the rope unwound from its drum without danger of said tongue swinging around against the operator. To re-engage the tongue and shaft or drum, the lever *H*, fulcrumed at *h'*, is depressed, so that its rear end, which rests under the shoulder *h*, will raise said shaft or drum to the position shown in Figs. 1 and 3. The key *i'* is now placed in the slot of the short shaft *i*, and the machine is thus made ready for another operation, the entire process occupying but a brief time in its accomplishment.

To entirely disconnect the shaft or drum *A* from the supporting-frame, the upper auxiliary cross-piece, *c*, is removed, when said shaft or drum can be lifted from its bearings, the tongue *L* being first disengaged and lifted off from the shaft or drum-head. 85

Having thus fully described my invention, what I claim as new, and desire to secure by Letters Patent, is—

1. In a stump-extractor, the drive-tongue having a bearing in its rear portion and an under block provided with a mortise, in combination with a shaft or drum journaled in a supporting-frame, and a short shaft and tenon formed integral therewith at its upper end, and a loose ring interposed between the under block of the tongue and said frame, and a lever fulcrumed to the latter and operating against a shoulder at the lower portion of the main shaft or drum, substantially as and for the purpose set forth. 90

2. In a stump-extractor, a supporting-frame having vertical standards and horizontal upper and lower cross-pieces, a shaft or drum journaled in said cross-pieces and provided with notches cut therein near its lower end, in combination with a guideway, a loose pulley-block having a tongue at its forward end, a drawing-rope secured at one end to a cross-piece of the frame and passed under and over pulleys in the loose block, and a pulley journaled in an upright of the supporting frame and secured to said shaft or drum, a drive-tongue detachably united to the latter, and spring-pawls pivotally connected to blocks upon the lower horizontal cross-piece, substantially as and for the purpose set forth. 105

3. In a stump-extractor, a supporting-frame having vertical standards, one of which standards is provided with a slot and a stirruped pulley journaled in said slot, in combination with a drawing-rope secured at one end to a shaft or drum and at the other to a cross-piece of the frame, a loose block operating in a guideway at the forward end of the frame and having journaled therein pulleys, around which the drawing-rope passes, a guide mechanism for the rope, consisting of a traveler-frame having journaled therein suitable pulleys, and a weighted cord secured at one end to a hanger upon one of the vertical standards, and a drive-tongue keyed to said shaft or drum, substantially as and for the purpose set forth. 115

4. In a stump-extractor, a frame having

vertical standards and horizontal cross-pieces, the upper one of the latter formed of two sections having their central portions cut away to form a bearing, and the lower one also formed with a central bearing, a removable shaft or drum journaled in said horizontal cross-pieces and provided with notches near its lower end and a tenon and slotted short shaft at its upper extremity, in combination 10 with spring-pawls pivotally connected to blocks upon the lower horizontal cross-piece, and a driving-tongue having a bearing for the short shaft and an under block formed with a mortise to engage the tenon of said drum or 15 shaft, and a key adapted to enter the short slotted shaft, substantially as and for the purpose specified.

5. In a stump-extractor, the driving-tongue composed of a main piece and rear brace-pieces 20 suitably united and provided with a spring-equalizer at its forward end, in combination with a shaft or drum journaled in a supporting-frame and formed with notches to engage spring-pawls, a drawing-rope secured at one 25 end to said drum or shaft and passed over a system of pulleys, a loose pulley-block traveling in a guideway at the forward end of the supporting-frame, bent stay-rods secured to the rear end of said frame, a connecting-rod 30 secured to a tongue at the forward end of the pulley-block, and chains for uniting said stay and connecting rods to the point of resistance and stump to be extracted, substantially as specified.

35 6. A stump-extractor consisting of a supporting-frame, a detachably-connected guide-

way at the forward end thereof, a shaft or drum journaled in said frame and provided with notches near its lower end, and a correspondingly-notched binding-ring, said shaft 40 or drum also formed with a tenon and slotted short shaft at its upper extremity, a drive-tongue having a mortised under block, a bearing in its rear portion, a key adapted to fit the slot in the short shaft, an interposed collar 45 between the mortised under block and the supporting-frame, in combination with the pivotally-secured spring-pawls, a shifting-lever fulcrumed to the supporting-frame, a loose pulley-block operating in the guideway and 50 provided with a tongue at its forward end, a drawing-rope secured to the shaft or drum, and passing around a system of pulleys and made fast to said supporting-frame, the rope-guide mechanism composed of traveler-frame 55 having journaled therein suitable pulleys and suspended by a weighted cord attached to a hanger, the bent stay-rods secured to the rear of the supporting-frame, the connecting rod or rods, and a shackle having a central web 60 and U-shaped ends, all arranged to operate substantially as described, and for the purpose set forth.

In testimony that I claim the foregoing I have hereunto set my hand, at Milwaukee, in 65 the county of Milwaukee and State of Wisconsin, in the presence of two witnesses.

WILHELM SCHUSTER.
